W. A. Harvey

UNITED STATES PATENT OFFICE.

THOMAS W. HARVEY, OF NEW YORK, N. Y., ASSIGNOR TO JOHN B. TERRY.

MACHINE FOR STICKING PINS.

Specification of Letters Patent No. 10,385, dated January 3, 1854.

To all whom it may concern:

Be it known that I, THOMAS W. HARVEY, of the city, county, and State of New York, have invented, made, and applied to use certain new and useful Improvements in Machinery for Sticking Pins into Paper; and I do hereby declare that the following is a full, clear, and exact description of the construction and operation of the same, reference being had to the annexed drawing, making part of this specification, wherein—

Figure 1, is a plan of the machine. Fig. 2, is a vertical section. Fig. 3, is a plan of the crimping jaws, and Fig. 4, is a side elevation.

15 The like mark of reference designate the same parts in all the figures.

The nature of my invention consists in cutting off by means of a slide or its equivalent one row of pins from the conductors, 20 so that one pin from the supply in each conductor is dropped, to be taken out by forceps and stuck into the paper.

A, is the bed of the machine.

25 a, is the driving shaft, propelled by any competent power, and sustained in standards 1, on the bed.

The paper to be crimped and receive the pins is supplied from a roll B, and the 30 paper with the pins thereon is drawn away to cause the requisite feed, by means of the drum C and apron driven by a ratchet wheel as now usual.

2, 2, are slides on the bed A, receiving by 35 a cross bar the double crimping blades b, b; and c, is a single blade similarly set on a cross bar in the slides 2, entering between the blades b, when each cross bar and their blades attached are given a motion in the

40 slides 2, the bar and blades b, being moved by arms 4, entering slots in the cross bar and attached to a shaft 3, that is given a partial rotary motion by an arm 5, to a cam 6, on the main shaft a, which cam b, is of

45 such a shape that at the proper time the end of the arm clears the cam allowing a spring 7 to throw back the blades b, out of the way. A similar attachment and motion is applied to the blade c, 8, being the shaft

50 with arms 9 to move the blades and 10, is the arm to the cam 11, 12, being the returning spring.

d, and e, are a pair of jaws one above and the other below the blade c, and so formed 55 as to allow the motion of this blade; the jaws being kept open by a spring x. The

jaws d and e, are set on center pins 13 and 14, and provided with arms f and g, with pins or rollers on their ends, on each side of the shaft a, which pins and arms are 60 operated on by cams 15 and 16, on opposite sides of the shaft a, by which the moving ends of the jaws are forced together.

The parts being timed and the paper being led in as shown in Fig. 2, the blades b, and c, 65 approach each other by the rotation of the shaft a, the blade c, passing within the blades b, forms the required center fold, at the same time the jaws d and e, commence to impinge on each side of the blades b, 70 folding the paper; at this moment the cam 11, passes the end of the arm 10, and the spring 12, throws the center blade out of the way; and at the moment the requisite pressure is obtained on the paper by the 75 jaws d, and e, the cam 6, passes the end of the arm 5, and its spring 7, throws the blades b, back, and the jaws d and e, coming together hold the four thicknesses of paper as shown in Fig. 5, ready for the pins to be 80 stuck through it.

The operation of sticking may be performed by any competent means, but I have herein shown my particular means for accomplishing this purpose. The edges of the 85 jaws f and g may have notches, see Fig. 3, similar to the old hand bar to support the paper as the pins pass through.

In Fig. 6, the center bar is shown stationary instead of being movable, the blades b, 90 passing on each side of the bar and the jaws d and e, holding the paper on each side of the stationary jaw, which arrangement is a mere substitute for the center blade c.

h, is a cam on the end of the shaft a, with 95 a pin 17 in its face that each revolution of the shaft gives a slight motion to a lever 18, on a fulcrum 19, the opposite end of which takes the end of a sliding bar or rod 20, that is supported by guides on, and 100 is let into the face of the conductors i, which conductors are formed as usual to pass the shaft of the pin and suspend it by the head and are in number corresponding to the number of pins to be stuck in each row, 105 the pins being supplied by a shaking hopper or hoppers in any manner similar to that now in use.

The bar or rod 20, is provided with notches in the edge that set against the upper part of the conductors, and made with holes through the bar, and on the edge of

the bar are points corresponding in number to the number of conductors, shown large size in Fig. 7, which points slide in a groove beneath the surface of the conductors. As 5 the rod is given an endwise motion these points enter above and behind the pins of the lower row as they stand in the conductors and prevent any more from descending; the row of pins thus cut off pass into the 10 notches in the bar and drop through the holes in the same into the lower part of the conductors, and on the bar going back the blank part of the bar comes opposite the ends of the conductors stopping the pins 15 from passing, thus depositing one row of pins each revolution of the shaft.

6 *k*, is a lever see Fig. 4, with a pin 22, operated on by the edge of the cam *h*, and 23, is a spring to keep the lever to the cam. 20 *l*, is a rod connecting the lever to an arm 24, on a cross shaft *m*, supported in standards 25.

7 *n*, is a bed fixed on the shaft *m*, receiving a sliding bed *o*.

25 *o*, is a bar attached by springs to the lower end of the bed *n*, so that when the parts are in the position shown in Fig. 2, the bed 26, sets against the ends of the conductors *i*. The upper edge of the bar 26, and 30 the lower edge of the bed *o*, are inclined as shown, for a purpose hereafter set forth.

27 is a holding jaw on a fulcrum 28, and 29 is a spring to keep the jaw open when not otherwise acted on.

35 *30*, is a spring latch on the upper end of the side of the holding jaw, which sides are connected by the bar *p*.

31, is a catch attached to the shaft *m*, in such a position and of such a length that 40 when the bar *p*, is forced toward the bed *n*, the latch 30, springs behind the face of the catch, the holding jaw 27 at the same time being made to pass beneath the heads of the pins and retain them as deposited by 45 the conductors, the heads being beneath and within a groove across the lower edge of the bed *o*. The holding jaw and parts connected are actuated by an arm 32, on a cross shaft *q*, with a lever 33, moved at the right 50 time by a pin 34, on the shaft *a*.

55 *r*, is a bent lever on a fulcrum 35, the upper end being formed as a slot to take a prolongation of the fulcrum pin 28.

36, is a pin or cam on the shaft *a*, to actuate this lever, and 37, is a spring to return the parts.

60 The operation of the stitching motion is as follows; the parts being properly timed relatively to the crimping. The pins being deposited as before described against the bar 26, and with the heads in the groove across the lower edge of the sliding bed *o*,

the arm 32, moved by its cam 34, on the shaft *a*, forces the bar *p*, toward the bed *n*, and the spring latch 30, holds the parts in 65 place, the jaw 27 retaining the pins; at this moment the cam *h*, by the lever *k* and rod *l*, gives the shaft *m*, sufficient of a rotation to bring the beds *n* and *o*, vertical in which 70 position the parts are retained by the circular shape of the cam till the pins are struck. The cam 36, now comes into operation and by the lever *r*, slides the bed *o*, downward (the inclined lower edge of which forces the spring bar 26, back out of the way) 75 sticking the pins into the paper and forcing them down below the lower edge of the spring bar 26, at this moment the point of the spring latch 30, sliding with the bed *o*, descend below the lower edge of the retaining catch 31, allowing the spring 29 to remove the jaw 27 from its hold of the pins and the cam 36, clearing the lever *r*, the spring 37 slides the bed *o*, up again and the pin 22, passing off the outer circle of the 80 cam *h*, the spring 23, brings the parts back 85 ready to receive another row of pins and again perform the motions as before detailed.

It will be evident that if the pins should 90 not be held parallel to each other when passing in the forceps from the end of the conductors to their vertical position for sticking, a comb may be fitted to take the shafts of the pins near their heads below 95 the clamp 27, and by a sliding motion to near their points straighten them, and bring them into the position for sticking.

It will be evident that the cams and parts that operate on the crimping jaws, and on 100 the holding jaws *d* and *e*, may be varied to suit the circumstances, and that the jaws for crimping and holding the paper may be placed vertically instead of horizontally and be used with any other means for sticking 105 the pins, and also that the method of carrying a row of pins from the ends of a series of inclined conductors may be used with any other character of crimping bars or blades.

What I desire to secure by Letters Patent 110 is—

I claim allowing one pin at a time to pass down the conductors by means of a vibrating slide or its equivalent so as to supply one row of pins at a time by the conductors to the forceps as specified.

In testimony whereof I have hereunto set my signature this seventh day of March one thousand eight hundred and fifty-three.

THOS. W. HARVEY.
